(57) **CLAIM**

The ornamental design of a fire starter tool, as shown and described.

DESCRIPTION

FIG. 1 is a front left perspective view of a fire starter tool; FIG. 2 is a rear right perspective view of a fire starter tool;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top plan view thereof; and,

FIG. 8 is a bottom plan view thereof.

The broken line portions of the figure drawings are included to show unclaimed subject matter only and form no part of the claimed design.
